UNITED STATES PATENT OFFICE.

MAGNUS UNGER, OF PITTSFIELD, MASSACHUSETTS, ASSIGNOR TO GENERAL ELECTRIC COMPANY, A CORPORATION OF NEW YORK.

INDUCTION-FURNACE.

1,326,120.

Specification of Letters Patent. Patented Dec. 23, 1919.

Application filed April 21, 1919. Serial No. 291,615.

To all whom it may concern:

Be it known that I, MAGNUS UNGER, a citizen of the United States, residing at Pittsfield, in the county of Berkshire, State of Massachusetts, have invented certain new and useful Improvements in Induction-Furnaces, of which the following is a specification.

The present invention relates to induction furnaces and comprises various structural improvements increasing the efficiency and durability of induction furnaces.

Although it has been suggested in a theoretical way to build induction furnaces having the primary winding located entirely above the container for the charge which constitutes the secondary winding, within my knowledge no furnace embodying such a construction has been placed in practical operation. It is possible that certain limitations which were believed to be inherent in such a construction have interfered with the practical use of this structure, as for example, the belief that it is necessary to locate the legs of the core outside the essential parts of the leakage field of the primary winding and the charge constituting the secondary. Such a construction would necessitate a larger core with corresponding increase in cost, core loss and exciting current. I have found that the reduction in stray flux would be negligible.

I have discovered that it makes no appreciable difference in the power factor of the furnace to place the legs of the core closely to the primary winding and the charge container.

It is the object of my invention to provide an induction furnace having a primary winding located above the charge container and embodying the above and other improvements hereinafter pointed out with particularity in the appended claims.

A complete understanding of my invention may be had from the following description taken in connection with the accompanying drawings. Figure 1 is a top view; Fig. 2 is a vertical section of a furnace embodying my invention; Figs. 3 and 4 illustrate structural details; and Fig. 5, Figs. 6, 6^a and Figs. 7, 7^a illustrate arrangements and electrical connection of the primary winding.

Referring to the drawing and particularly to Fig. 2, the furnace comprises a magnetic core consisting of vertical legs 1, 2, 3, a horizontal lower yoke 4 and a horizontal upper yoke 5 connecting the vertical legs 1, 2 and 3. The primary winding comprises a flat coil 6 consisting in some cases of several interconnected sections, as hereinafter described in connection with Figs. 5, 6 and 7. The terminals 7, 7' of the primary winding are shown in Fig. 1.

The charge to be treated is contained within an annular crucible 8 located beneath the primary winding 6 and surrounding the central leg 2 of the core. The crucible 8 is provided with an outer shell 9 of steel, or other suitable metal, which has one or more insulated joints to break the electric circuit. It is lined with a layer of fire brick 10, inside of which is an inner lining 11, consisting of highly refractory material, as, for example, crystallized magnesia, preferably, magnesia which has been molten, allowed to crystallize and thereupon powdered and rammed into place with a suitable binder.

As shown in Fig. 2 of the drawing, the side walls of the crucible are outwardly inclined so as to make an angle with respect to each other of about 60 to 90°, that is, lines passing through the intersection of a vertical plane with the opposite side walls meeting at an angle within the limits of about 60° to 90°.

This construction has the following advantages: (1) It provides a shallow furnace chamber in which a given amount of charge, such as melted steel, can be brought closer to the primary winding 6 than in a deep narrow furnace chamber; (2) the position of the walls enables them to be easily repaired when cracked or worn out by the action of the charge and the slag; (3) the meniscus of the melted charge is more nearly flat and hence there is less slag required to completely cover the melted metal than in a deep narrow chamber in which the meniscus is driven down on one side and up on the opposite side by the magnetic action of the stray flux to a greater degree than in a shallow chamber; (4) the heating action of the current induced in the charge is greatest at the surface, that is, nearest the primary winding. Hence in a wide, shal-

low crucible the chemical action of the slag is distributed over a greater surface of highly heated metal than in a narrow deep chamber; (5) the circulation of the charge 5 in a plane perpendicular to the direction of the electric current is less erosive on a crucible when the direction of this motion is substantially parallel to the wall. Further mention of this fact will be made in 10 connection with Figs. 6^a and 7^a. When the walls have the angular relation above assigned it has been found that the erosion is less than in more nearly vertical walls.

The crucible is provided with a cover 12 15 of silica fire brick, crystallized magnesia, or other suitable refractory material. The cover 12 is preferably provided with rings 13, 14, of iron or the like, on its inner and outer side walls, and these rings may be provided 20 with bands 15, 16 to which hooks may be applied for convenience of removal of the cover 12, as indicated at 17.

The primary winding 6 is provided with a casing or housing 20, consisting of non-magnetic material, such for example, as brass, or 25% nickel steel. The central leg 2 of the core is provided with casing 21, spaced away from the core and providing space for the passage of the cooling fluid, 30 such as air. The lower end of the casing 21 connects with an inlet tube 22 and the upper end registers with an inlet opening into the casing 20. A blast of air received through the inlet tube 22, passes around 35 the core 2 and from thence around the coil 6, finally emerging through outlet opening 23 at the periphery of the casing 20. Preferably openings 24 are provided for the passage of some of the cooling air over the top 40 of the cover 12.

Circular angle irons 26 and 27 rest upon the yoke 5, and act as supports for the primary coil 6 and its surrounding casing which are connected thereto by studs 28. 45 Preferably, the cover 12 is also connected to one of the angle iron supports, for example, by connecting rods 17, already referred to. This construction enables the yoke, primary coil, its casing and the cover of the 50 furnace to be removed as a unit, the bolts 29 connecting the yoke 5 to the vertical legs of the core being first removed. In this manner convenient access may be had to the charge within the crucible, which is then 55 entirely exposed.

The entire furnace is supported within a frame 31, hung by the shaft 32 on trunnions 33, so as to enable the furnace to be tilted by any convenient means, such as the hand 60 wheel 34, for the removal of the charge.

As shown in Fig. 1, a number of charging doors 35, 36, and 37 may be provided for the introduction of metal to be melted, slag forming materials and the like. Convenient 65 access is provided thereby to all parts of the

charge in the crucible, rendering convenient the supervision of slagging operations and the like. A pouring spout 38 is provided for the discharge of the metal and slag.

The magnetic core of the furnace is so proportioned and designed that the magnetic flux density will be substantially uniform when the furnace is under load. The limiting feature determining the size of the 75 core of an induction furnace is generally not the core loss which is relatively low on account of the low frequencies used. On the other hand, the factor which is of considerable importance is the exciting current required for the primary windings. The greater the exciting current the lower will be the power factor at which the furnace will operate. By proportioning the core to give a substantially uniform flux density at load 80 current, there will be a substantial reduction in the core loss as well as in the exciting current under load conditions. The lower yoke 4 of the core because of its more remote location from the primary and secondary 85 winding has a lower flux density than the upper yoke 5. This is not only in accord with theoretical considerations taking into account the leakage fields but has been 90 experimentally determined by me.

In order to operate the furnace with a substantially uniform flux density I give the largest cross-section to the top yoke 5 as this will have nearly the same flux density as at no load. The vertical legs 1, 2 and 3 100 will have cross-section 10 to 25% less and the bottom yoke 4 will have cross-section 25 to 50% less than the cross section of the top yoke. The actual proportion of the sections will depend upon the particular design and 105 is based upon the distribution of the stray flux. In this manner the weight of the core may be reduced without sacrifice of efficiency. For example, in a 20-ton induction furnace a core designed to give a uniform 110 flux density of no load, would weigh forty tons. The weight of such a core in a furnace of the design illustrated herewith could be reduced about 15% or more in weight of material with a correspondingly reduced 115 cost.

There is always some danger in an induction furnace of a fracture of the lining and the escape of molten metal through the break with consequent damage to the core 120 and other parts of the furnace. As already indicated above, I have provided a shield about the core to obviate damage by the escape of molten metal.

Figs. 3 and 4 illustrate in section specific 125 forms of shields embodying my improvement. The shield illustrated comprises a metal form 41 upon which are located a layer 42 of refractory fire-proof material such, for example, as mica, and an outer 130

layer 43 of fibrous refractory material, such as asbestos. As asbestos fabric loses part of its mechanical strength at a temperature of about 200° to 300° C. due to a burn-out 5 of the cotton binder commonly used, I prefer to impregnate the asbestos with a binder, such as a phenolic condensation product. The heat insulating properties of asbestos and mica serve as adequate protection even 10 for molten steel at 1600° C. In some cases the metal backing may be omitted and in fact in some sizes of furnaces a layer of asbestos alone will furnish adequate protection.

Although in Fig. 2 the primary winding 15 of the furnace has been indicated as consisting of two sections, it is desirable in some cases to provide more than two sections. In any event, whether two sections or a greater number are used I provide connections and switching means for supplying 20 one of these sections or a combination of sections with current to the exclusion of the other sections in order to adjust the shape of the meniscus of the molten charge in the 25 furnace crucible. For example, in Fig. 5 I have shown a primary coil consisting of sections 45 to 48 provided with separate conductors 49 to 53, and respective switches 54 to 58. By closing switches 54 and 55 current 30 can be sent through section 45 while the remaining sections remain open-circuited, and in the same way by closing switches 54 and 56 while the remaining switches remain open current may be sent 35 through the sections 45 and 46 in series. In this manner the magnetic center of the excitation may be shifted from the inner toward the outer periphery of the furnace crucible. The effect of this is illustrated 40 more clearly in Figs. 6 and 6^a and 7 and 7^a. In Fig. 6 two groups of coils 59 to 62 and 63 to 66 are connected electrically in parallel through the conductors 67 and 68. In that case the molten charge assumes a shape 45 somewhat as shown in Fig. 6^a, a single circulatory current being set up in the bath as indicated by arrows. This single circulatory effect as distinguished from the double circulation is distinctive of a furnace built in accordance with my invention 50 having a shallow crucible with diverging walls. A single circulation as illustrated obviates the deleterious suction effect on the crucible wall caused by a double circulation. 55 With the shape of a meniscus shown in Fig. 6^a there is a depression at the point 69. This unevenness in the shape of the meniscus requires a larger amount of slag to fully cover the metal at the high point 60 70 of the bath than would be required with a more level meniscus. It is preferable therefore for some metallurgical operations to change the connections by shifting the switches 71, 72, 73, 74 and 75 to connect the 65 coils 59, 60, 63 and 64 in series, as indicated

in Fig. 7. With this connection the magnetic center is shifted to the outer periphery of the crucible and the meniscus of the charge assumes a more level shape, as shown in Fig. 7^a.

What I claim as new and desire to secure by Letters Patent of the United States, is:—

1. An induction furnace having a melting chamber, the side walls of which are outwardly inclined and make an angle of about 70 60 to 90° with respect to each other.

2. An induction furnace comprising a core, a primary winding, upon said core and a furnace chamber located below said primary winding and adapted to contain a charge, the 75 walls of said chamber being outwardly inclined about 60 to 90° with respect to each other.

3. An induction furnace comprising a magnetic core, a primary winding thereon 80 and a crucible located beneath said winding for containing a charge constituting a secondary winding, the legs of said core being placed closely about said primary and secondary windings within the leakage fields of 85 said windings.

4. An induction furnace comprising a core having a removable yoke, a primary winding upon said core, a charge-containing chamber located upon said core, a cover therefor, 90 means mechanically connecting together said yoke, cover and all parts above said chamber in order to enable the same to be removed as a unit in the operation of said furnace to expose a charge within said crucible.

5. An induction furnace comprising a core, a primary winding interlinked magnetically with said core, a housing for said winding, a removable yoke for said core, means 105 for mechanically connecting said yoke, winding and housing, and a charge containing chamber located beneath said primary winding.

6. An induction furnace comprising a core, 110 a removable yoke for said core, a primary winding interlinked magnetically with said core, a housing for said winding, having inlet and outlet openings, means attaching said winding and housing to said yoke and 115 a housing for said core providing space for a cooling fluid and communicating with the inlet of the housing for the primary coil.

7. An induction furnace comprising a core having a disengageable yoke, a primary 120 winding for said core, a crucible for containing a charge constituting a secondary winding, a cover for said crucible and means connecting said yoke, primary winding and cover to enable the same to be removed as 125 a unit.

8. An induction furnace comprising a core, 130 a charge container surrounding said core, a primary winding consisting of a plurality of sections located upon said core above said

container, and switching means for varying the electrical connection of said coils to each other.

9. An induction furnace comprising a core, a refractory container adapted to contain the charge constituting the secondary winding of the furnace and a primary winding for said furnace consisting of a plurality of sections, and switching means exciting one or more of said sections to the exclusion of other sections in order to vary the relation of the magnetic center of said primary winding to the furnace charge.

10. An induction furnace comprising a primary winding thereon, a crucible adapted to contain the charge constituting the secondary winding, a core of magnetic material linking said windings, said core being located in part beneath said crucible thereby subject to contact with the accidental escape of

molten material through a fracture in said crucible, and a shield located between said crucible and parts of said core exposed to damage from escaping charge.

11. An induction furnace having a core 25 of non-uniform cross-section, said core being proportioned to have a substantially uniform flux density when the furnace is operating at load.

12. An induction furnace comprising a core, 30 a primary electrical winding therefor, and a crucible adapted to contain a charge constituting a secondary winding, the cross-section of said core being proportioned to give substantially uniform flux density when 35 said furnace is operated at load.

In witness whereof I have hereunto set my hand this 18th day of April, 1919.

MAGNUS UNGER.
